COMBINED HANDLE AND TRIM STRIP FOR SUCTION CLEANER

Raymond Descarries, Montreal, Quebec, Canada, assignor to Aktiebolaget Electrolux, Stockholm, Sweden, a corporation of Sweden

Application April 1, 1958, Serial No. 50,285

Term of patent 14 years

(Cl. D9—2)

FIG. 1

FIG. 2

FIG. 3

FIG. 4

FIG. 5

FIG. 6

Fig. 1 is a perspective view of a combined handle and trim strip for a suction cleaner showing my new design;
Fig. 2 is a side elevational view thereof;

Figs. 3 and 4 are respectively top and bottom plan views thereof; and

Figs. 5 and 6 are respectively front and rear elevational views thereof.

I claim:

The ornamental design for a combined handle and trim strip for a suction cleaner, as shown.
